UNITED STATES PATENT OFFICE

1,961,820

SIGNALING SYSTEM

Norvel Douglas, Lawrence, Kans., assignor to
 General Electric Company, a corporation of
 New York

Application October 7, 1929, Serial No. 397,893

7 Claims. (Cl. 179—171)

My present invention relates to signaling systems including oscillation generators of the type disclosed in copending application, Serial No. 389,-067, filed August 28, 1929 by Elmer D. McArthur, 5 entitled High frequency magnetron apparatus, and which is assigned to the same assignee as the present application. It has for its purpose to provide means whereby oscillations produced by generators of the type indicated may be modulated 10 in accordance with desired signals.

The novel features which I believe to be characteristic of my invention are set forth with particularity in the appended claims. My invention itself, however, both as to its organization and 15 method of operation, together with further objects and advantages thereof, may best be understood by reference to the following description taken in connection with the accompanying drawing in which Fig. 1 represents one embodiment 20 of my invention, and Fig. 2 represents a modification thereof.

Referring to Fig. 1 of the drawing I have shown at 1 an electron discharge device comprising a pair of oppositely disposed anodes 2 and 3 which 25 are arranged in substantially cylindrical formation about a filamentary cathode 4. Connected between the anodes is an inductance 5 and, if desired, a capacity 6 forming an oscillatory circuit. This oscillatory circuit also includes of course the 30 inherent capacity between anodes 2 and 3. Where the system is to be used for the production of ultra high frequency oscillations the external capacity 6 and concentrated inductance 5 may be removed, the inherent capacity between the 35 anodes and the inductance of the anode leads comprising the entire oscillatory circuit. The cathode 4 is heated by means of an energy source 7, and the anodes are supplied with energy from a direct current source 8 through a reactor 9 40 which is connected to the mid-point on the inductance 5.

Encircling the discharge device 1 is a coil 16 which is energized from a source of unidirectional electromotive force 17 having a value such that 45 the oscillations produced in the circuit 5, 6 are of desired intensity. By this means a magnetic field is produced between the anodes 2 and 3 the lines of force of which extend parallel with the axis of the cylinder formed by the anodes and hence 50 parallel with the cathode.

It has been found that the amplitude of oscillations produced by a generator of the type indicated vary directly with the intensity of the magnetic field as indicated in copending application 55 of Elmer D. McArthur, Serial No. 320,709, filed

November 20, 1928, entitled "Signal transmitting means" and which is assigned to the same assignee as the present application, and that with a constant value of field current the oscillations vary inversely as the anode potential through a certain range thereof. In the manner presently to be described the anode potential may be varied in response to signal currents, such as those produced by a microphone, or a like signal device, and in this manner, modulation of the intensity of the oscillations produced in accordance with the signal currents may be efficiently accomplished.

As shown in Fig. 1 this result is attained by means of an electron discharge device 10, the space between the anode and cathode of which, is connected in shunt with the series connected reactor 9 and source 8. Signal currents produced in the microphone, or in any other suitable signal device 11, may be supplied to the grid of the device 10 through an amplifier 12. Normally the grid of the device 10 is biased negatively by means of a source of potential 13 to a degree such that the magnitude of current flowing in the anode circuit produces the normal anode dissipation of the discharge device. When signal currents are applied to the grid of device 10 this grid becomes less negative, or positive, with respect to the cathode and the impedance between the cathode and anode is thereby reduced. Hence an increase in current from the source 8 through reactor 9 and the space between the anode and cathode of device 10 will occur. This change in current in the anode of the device 10 induces a voltage in reactor 9, which is opposed to that of the source 8 and which causes a diminution of potential on the anodes and a corresponding increase in the intensity of oscillations produced. When the potential on the grid of device 10 changes in the opposite direction the voltage induced in reactor 9 aids that of source 7 and causes a corresponding decrease in the intensity of oscillations produced. In this way the oscillations produced may be efficiently modulated in intensity in accordance with the signals produced by the device 11.

In the modification of my invention shown in Fig. 2 the oscillatory circuit 5, 6, is in the form of a series resonant circuit connected between one of the anodes and the cathode. Also in this figure the two anodes are maintained at different potentials, the potential on the anode 3 being higher than the normal potential on the anode 2, this potential being supplied by means of a source 15 connected between the anode 3 and the

cathode. The potential on the anode 2 is supplied by a source 15 connected between the cathode and the anode 2 through the reactor 9. It has been found that, with a fixed value of potential of the source 14, and with the field current suitably adjusted, that for a certain range of voltages on anode 2 less than that on anode 3 the discharge device has negative resistance between the cathode and the anode 2, that is, as the potential of the anode increases the current flowing between the cathode and the anode decreases. If the oscillatory circuit 5, 6 be connected between the anode 2 and the cathode and the potential on anode 2 is adjusted within the negative resistance range it will be found that oscillations are produced in this circuit. These oscillations may be modulated in the manner described in connection with Fig. 1, the anode cathode circuit of discharge device 10 being connected in shunt with the reactor 9 and source 15.

The load circuit upon the oscillation generator may be coupled to the oscillatory circuit by any form of coupling well known in the art although as shown in the drawing an inductive coupling represented by transformer 5, 18 is employed.

While I have shown but a particular means for modulating the oscillations it will of course be understood that I do not wish to be limited thereto since other means may be employed for accomplishing the purpose as, for example, that of varying the field current by means of a microphone connected in that circuit.

While I have shown particular embodiments of my invention, it will of course be understood that I do not wish to be limited thereto since many modifications, both in the circuit arrangement and in the instrumentalities employed, may be made without departing from the spirit and scope of my invention, as set forth in the appended claims.

What I claim as new and desire to secure by Letters Patent of the United States is:

1. In combination, an electron discharge device comprising a pair of oppositely disposed anodes, a cathode extending between said anodes, means for producing a magnetic field between said anodes, a resonant circuit connected to said cathode and to at least one of said anodes, means for supplying potential to said anodes whereby oscillations are produced in said resonant circuit having a frequency determined by the characteristics of said resonant circuit, said magnetic field between said anodes being maintained constant during the production of said oscillations, a source of continuously variable signal current, and means for modulating the amplitudes of oscillations of said frequency in accordance with the continuous variations in said signal current.

2. In combination, an electron discharge device having a pair of oppositely disposed anodes, a cathode extending between said anodes, a resonant circuit connected between said anodes, means for producing a magnetic field between said anodes, means for impressing positive potential on said anodes, a source of continuously variable signal current, and means connected between the anodes and cathode for modulating the oscillations produced in accordance with the continuous variations in said signal current.

3. In combination, an electron discharge device comprising a pair of oppositely disposed plate members, a cathode extending between said members, means for producing a magnetic field between said plate members and parallel with said cathode, a resonant circuit including the capacity between said plate members, means for supplying unidirectional potential to said plate members having value such that oscillations are produced in said resonant circuit, a source of continuously variable signal current, and means for varying said potential in accordance with the continuous variations in said signal current thereby to modulate the oscillations produced. 80

4. In combination, an electron discharge device, comprising a pair of oppositely disposed anodes, a cathode extending between said anodes, means for producing a magnetic field between said anodes, an oscillatory circuit comprising the inherent capacity existing between said anodes and an inductance connected between said anodes, a reactor connected between a point on said inductance and said cathode, means for supplying potential through said reactor to said anodes such that oscillations are produced in said oscillatory circuit, and means for varying the potential on said reactor in accordance with desired signals thereby to modulate the oscillations produced. 90

5. In combination, an electron discharge device, comprising a pair of oppositely disposed anodes, a cathode extending between said anodes, means for producing a magnetic field between said anodes, an oscillatory circuit comprising the inherent capacity existing between said anodes and an inductance connected between said anodes, a source of unidirectional potential and a reactor connected in series between a point on said inductance and said cathode, said potential being of value such that oscillations are produced in said oscillatory circuit, an electron discharge path connected in shunt with said series connected source and reactor, and means for varying the impedance of said path in accordance with desired signals thereby to modulate the oscillations produced. 100

6. In combination, an electron discharge device comprising a pair of oppositely disposed anode members, an electron emitting cathode extending between said members, means for supplying positive potential to both of said anode members, means for producing a magnetic field between said anodes, an oscillatory circuit connected to the cathode and to one of said anodes, the potential on said anodes being such that sustained oscillations are produced in said oscillatory circuit, and additional means connected across a portion of said oscillatory circuit to modulate the oscillations produced. 110

7. An oscillation generator comprising an hermetically sealed container wherein are contained an electron emitting cathode and a plurality of anodes, means for subjecting electrons flowing from said cathode to said anodes to a magnetic field, a tunable circuit connected to said anodes, a source of potential for polarizing said anodes with unidirectional potential, and means for varying the potential applied to the anodes in order to modulate the oscillations generated in said tuned circuit. 125

NORVEL DOUGLAS.
